Inventor:
Francis W. Robinson

UNITED STATES PATENT OFFICE.

FRANCIS W. ROBINSON, OF RICHMOND, INDIANA.

TRACTION-ENGINE.

SPECIFICATION forming part of Letters Patent No. 300,397, dated June 17, 1884.

Application filed March 14, 1884. (No model.)

To all whom it may concern:

Be it known that I, FRANCIS W. ROBINSON, a citizen of the United States, residing at Richmond, in the county of Wayne and State of Indiana, have invented certain new and useful Improvements in Traction-Engines; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

My invention relates to that class of engines known as "traction-engines," and which are self-propelling.

My invention consists in a spring-platform swung to the rear end of the boiler.

In the drawings, Figure 1 is a side elevation of a boiler with tank and spring-platform attached. Fig. 2 is a perspective view of the spring-platform and its means of attachment.

In Fig. 1, A represents a boiler of ordinary construction, of which M is the fire-box. a is the chimney. k is a water-tank which is secured to the front end of the boiler m.

n is a chamber or open space between the end of the flues and the boiler-head.

l is the man-hole opening into the tank k.

The tank has pipe-connections with the reservoir and boiler in any suitable manner, and the heat in the chamber n is communicated to the tank k and its contents.

D D', Fig. 2, represent metal arms hinged at one end to the fire-box, (seen at G, Fig. 1,) secured to which near their opposite ends are brace-rods C C', which are secured at their upper ends by hooks and eyes, at E, Fig. 1.

B is a rectangular platform placed upon the arms D D' by bolts I I' I" I".

Between the platform B and the arms D D' are placed coiled springs H H' H" H", upon which the said platform has its bearings and relieves the occupant of the platform from the shaking and jarring of the engine.

I am aware that a removable platform swung from the rear end of the boiler has been used, and this I do not claim, broadly; but

What I do claim is—

In a road or traction engine, the platform B, resting upon springs H H' H" H", in combination with the frame D D', in the manner and for the purposes herein set forth.

In testimony whereof I affix my signature in presence of two witnesses.

FRANCIS W. ROBINSON.
